UNITED STATES PATENT OFFICE.

ALBERT H. BATES, OF CLEVELAND, OHIO, ASSIGNOR TO THE AMERICAN MULTIGRAPH COMPANY, OF CLEVELAND, OHIO, A CORPORATION OF OHIO.

DUPLICATING-MACHINE.

1,045,498.

Specification of Letters Patent.

Patented Nov. 26, 1912.

Application filed October 17, 1907. Serial No. 397,766.

To all whom it may concern:

Be it known that I, ALBERT H. BATES, a citizen of the United States, residing at Cleveland, in the county of Cuyahoga and State of Ohio, have invented a certain new and useful Improvement in Duplicating-Machines, of which the following is a full, clear, and exact description, reference being had to the accompanying drawings.

10 One of the objects of this invention is to provide a printing machine so arranged that type may be conveniently assembled thereon and distributed therefrom.

Another object is to provide simple and 15 effective means for causing the transfer of type between suitable type holders, as a storage member and a printing member. The invention may thus take a form similar in some respects to the machine commercially known as the multigraph.

In its preferred form of embodiment the present invention has a rotary printing drum adapted to carry lines of individual type, a storage drum, a platen coöperating 25 with the printing drum, an inking ribbon through which the printing is effected,—these features being the frequent ones in the multigraph. When so embodied, a peculiarity of the present invention lies in its 30 means for assembling and distributing. This is accomplished by swinging the machine so that either drum is uppermost as desired, the assembling or distribution from one drum to the other being accomplished 35 by gravity and lateral transference controlled by a suitable key. The invention includes means for accomplishing this operation broadly; it includes also the particular arrangement shown, and various 40 combinations of intermediate scope.

The invention may accordingly be most conveniently summarized as consisting of the combinations of mechanisms or parts hereinafter more fully described and set 45 out in the form of essential characteristics in the claims.

In the drawings, Figure 1 is a perspective view of my machine complete, showing also its supporting stand; Fig. 2 is a front 50 elevation of my multigraph proper; Fig. 3 is a vertical longitudinal section thereof, be-

ing on the plane indicated by the offset line 3—3 in Fig. 4; Fig. 4 is a vertical cross section substantially on the line 4—4 of Fig. 2; Figs. 5, 6 and 7 are cross sections through the intermediate frame member between the drums and a portion of each drum in different positions,—Fig. 5, showing the assembling position, where the storage drum is uppermost; Fig. 6, showing the normal position where the two drums are horizontal; and Fig. 7 showing the distributing position where the printing drum is uppermost; Fig. 8 is a vertical cross section through the intermediate frame member in its normal 65 position; Fig. 9 is a perspective of the type employed; Figs. 10 and 11 are views of correcting implements.

Referring to the parts by reference numerals, 10 represents a suitable stand having an open top. Rising from the front and back of this stand are standards 11 and 12. Journaled in these standards is my multigraph proper, which includes the frame 13, having end members 14 and 15 and intermediate members 16, a storage drum 17 between the frame members 14 and 16, and a printing drum 18 between the frame members 15 and 16. The machine is carried by the standards by reason of journal pins 20 and 21 projecting inward from the standards 11 and 12 respectively, and occupying sockets in the intermediate frame member 16. The journal pin 21 is preferably screw threaded into the standard 12 and clamped by a nut 23, this construction enabling the easy removal of my multigraph. The three frame members mentioned are rigidly braced by through bars 25. The printing drum carries spools 28 upon which are adapted to be mounted a ribbon which may extend around the drum. The storage drum and printing drum are each formed with the usual overhanging T-rails, on which may be mounted the grooved type shown in perspective in Fig. 9.

29 indicates a small crank for adjusting the position of the eccentrically mounted platen 27.

30 and 31 indicate suitable paper feed 100 rollers which may be driven in any suitable manner, not shown.

This multigraph proper is normally held in horizontal position by suitable bolts extending through the frame of the stand and engaging the base of the multigraph, three of these bolts appearing at 33, 34 and 35 respectively.

From the above description it will be apparent that I have provided a rotary ribbon printing machine, and that it is only necessary for operation to assemble the type on the printing drum, pass the ribbon around it, rotate the printing drum, and feed the paper between the drum and platen, this being the usual multigraph operation. The rotation of the drum is effected by a crank 40, which is connected with the drum in a manner hereinafter referred to. The assembling and distribution features, which constitute the primary novelty of this machine, will now be described.

Mounted in grooves in the opposite faces of the intermediate frame plate 16 are slides 41 and 42. These slides have openings 43 and 44 adapted to align with channels of the respective drums and receive the type. Each slide is the same thickness as a single type, and each of the openings 43 and 44 is provided with a pair of short ribs 46 adapted to receive the grooves in the type. It will be noticed that the storage drum, as shown, is of larger diameter than the printing drum. Each of the slides 41 and 42 have sufficient movement to enable the corresponding opening 43 or 44 to align with either drum. Such movement of the slide therefore may cause the engagement of the lowermost type dropping from the uppermost drum and its transfer to position where it will drop into the lowermost drum, there being openings through the frame member 16 to allow such passage. This is briefly the operation of assembling and distributing and is the real reason for making one drum larger than the other, though it is also an advantage to have the storage drum larger in that it can carry more type.

Between the two slides 41 and 42 in the frame member 16 is a pair of openings 48 and 49, each of these openings having ribs 50. The opening 48 aligns with the front channel in the printing member, the ribs of these channels alining with the adjacent rails of the respective members which define the channels. Between the two openings 48 and 49 is a smaller connecting opening occupied by a block 52. This block is of a width from front to back of the machine equal to the width of one of the openings 48 and 49 plus the intermediate opening. From this it results that if the block is in its foremost position the type channel 49 is open, the type channel 48 being interrupted and effectively closed by the presence of the block therein. On the other

hand, if the block is in its rearmost position, the type channel 48 is open and the channel 49 is blocked. In its intermediate position both channels are partially blocked.

The slide 41 is given a tendency to assume its foremost position by a spring 53 connected at its forward end to a stationary pin 54, and at its rear end to a pin 55 projecting from the slide, the slide being slotted around the pin 54. The slide 42 is given a tendency to assume its rear position by a spring 57 connected at its rear end with stationary pin 58 and at its forward end to a pin 59 projecting from the slide 42. Mounted in openings 60 and 61 in the frame member 16 are two short levers 63 and 64, each of which is pivoted in position and has connected with its short arm beyond its pivot a link 65, 66, the other end of which is connected with the block 52. The free ends of these levers 63 and 64 engage slots 67 and 68 in the corresponding slides 41 and 42. The slide 41 is provided at its forward end with a finger key 70 rigid therewith, by which it may be easily pushed rearward; while the slide 42 is provided at its forward end with a finger key 71 in the form of a hook by which the slide may be drawn forward.

In the block 52 is an opening 72 which is occupied by an eccentric 73 on a shaft 74. At its lower end this shaft carries a gear 75 meshing with a pinion 76 on a shaft 77 which carries a bevel gear 78 meshing with a stationary beveled rack 79 formed on the rear face of the standard 11 and on the rear face of arc shaped arms 80 extending therefrom.

Fig. 6 shows the normal position of the transfer mechanism above described. That is, when the two drums are horizontal and the machine is in position for printing. In this position the eccentric 73 holds the block 52 in its intermediate position, and this block holds the levers 63 and 64 in their intermediate position, and these levers hold the two slides in intermediate position, each of the springs 53 and 57 being somewhat stretched. In this position of the parts the openings 43 and 44 are out of alignment with their respective drum channels, so that no escape of type at the ends of the drums is permitted. The outer face of each slide aligns with the raised surface 83 or 84 of the frame member 16, which stands opposite the ends of the channels in their respective drums and forms an end gate therefor.

When it is desired to assemble, the machine is turned with the storage drum uppermost, as shown in Fig. 1. This brings the transfer mechanism into the vertical position shown in Fig. 5. The rotation of the multigraph through this quarter circle gives the eccentric 73 a quarter turn toward the front, by reason of its connecting gearing 130

with the rack 79. This shifts the block 52 into its extreme forward position, closing the opening 48 and fully unblocking the opening 49. At the same time, the lever 63 b shoves rearward the slide 41, so as to bring the opening 43 into alinement with the opening 49 and the channel of the printing drum directly beneath this opening. At the same time, the lever 64 swings backward at 10 its upper end and allows the spring 57 to pull the slide 42 rearward to bring its opening 44 into alinement with the opening 49. Now in this position of the parts to assemble the type it is only necessary for the operator 15 to engage with his finger the key or hook 71 and draw the slide forward until the opening 44 is beneath the row of type in the channel of the storage drum above this slide. This channel is indicated by 85 and 20 the type by 86. As the slide comes into its foremost position (defined by the stop screw 89 in the slot 90) the lowermost type in the row 86 drops into the opening 44; then as the operator's hold on the hook 71 is released 25 the spring 57 returns the slide to its rear-most position, carrying the type directly over the opening 49. The type thus drops by gravity through the opening 43 into a channel 87 of the printing drum directly beneath these openings.

When it is desired to distribute type from the printing drum to the supply drum, the multigraph is swung in the opposite direction a quarter turn. This brings the printing drum uppermost and brings the transfer mechanism into the position shown in Fig. 7. The gearing between the eccentric and the stationary standard has swung the eccentric into the rearmost position, thus 35 ing drum uppermost and brings the transfer mechanism into the position shown in Fig. 7. The gearing between the eccentric and the stationary standard has swung the eccentric into the rearmost position, thus 40 causing the block 52 to close the opening 49 and unblock the opening 48. The levers 63 and 64 have now released the slide 41 to let its spring draw it in the foremost position and have shoved the slide 42 against 45 its spring into the foremost position. In this position, therefore, there is an open channel to the supply drum provided by the openings 43, 48 and 44. To transfer the type from the printing drum to the supply drum 50 it is therefore only necessary to shove the slide 41 rearward by pressure on the key 70. In its rearmost position (defined by the pin 54 in the slot 91) the lowermost type 83 in the channel 87 drops into the opening 43. 55 Then as the pressure on key 70 is released, the spring 53 draws the slide back into its foremost position, thus distributing the type into the forward alined openings 48, 44, and dropping it into the channel 85 60 of the supply drum. It will be noticed that whichever drum is uppermost, its key, 70 or 71 as the case may be, is the only one in position for engagement by the operator's finger, the other key being behind the stand- 65 ard 11 and inaccessible.

From the above description it will be apparent that all that is necessary to assemble type from various channels of the supply drum into a channel of the printing drum, or to distribute type from a channel of the printing drum to the various channels of the supply drum, is to turn the machine so that the drum from which the type are to move is uppermost and the drum to which they are to go is lowermost, and then turn the supply drum to bring its desired channel into position and operate the available key.

To enable the supply drum to be conveniently turned whichever drum is uppermost, I arrange hand wheels 92 and 93 at each end of the machine, each wheel being connected with the supply drum. As shown, the supply drum is rigid on a through shaft 94, and the two hand wheels are rigid on the corresponding ends of this shaft. The printing drum is mounted on a sleeve 96 which bears at one end on a tubular bushing 97 projecting from the frame member 16 and at the other end projects through to frame member 15, a crank 40 being mounted on this projecting end of the sleeve 96. Within this projecting end is a bushing 97, in which the shaft 94, bears at that end. Thus whichever end of the multigraph is uppermost there is always at the top of the machine during the transfer a hand wheel by which the storage drum may be turned to bring the desired channel into alinement with the channel of the transfer mechanism.

To form a simple indicator to assist in positioning the storage drum, I form on the periphery of each of the hand-wheels a chart 98 arranged in the order of the characters in the supply drum. These charts co-operate with a pointer 99 at one end of the machine and a pointer 100 at the other end. The crank 40 is so formed that its handle projects beyond the hand wheel 93, allowing convenient rotation of the drum. In such rotation, this crank passes over the pointer 100. I therefore mount this pointer slidably in a standard 101. When the pointer is telescoped into its standard, as shown in full lines in Fig. 2, the crank may be operated, passing freely thereover. When the printing drum is uppermost in distributing, the pointer is elevated to co-operate with the chart 98 on the hand wheel 93. The crank 40 projects in the radial direction toward the opening in the periphery of the drum occupied by the spools 28, as in distributing this opening is never opposite the transfer mechanism, so that the crank never comes in the way of the elongated pointer 100.

It is desirable during the printing operation to lock the supply drum, its shaft and hand wheels to prevent any unnecessary rotation being communicated thereto from the rotation of the printing drum. This I ac-

- 4
- complish by a bolt 102 mounted in a hub 103 projecting from the frame plate 14, the bolt being adapted to enter a notch 104 in the band wheel 92 and thereby lock it and the supply drum against accidental rotation.
- 5 10 In order to allow corrections to be easily made during or after assemblage of the matter on the printing drum, I provide on the inner face of the supply drum a spring clip, indicated by 125 in Fig. 3, so positioned that it may hold a split tube 126 (Fig. 19) parallel with the axis of the drum and directly over the opening 49. The walls of this tube are resilient, wherefore it is adapted to retain type. In case the wrong character has been transferred to the printing drum, the supply drum may be turned into proper position, the split tube inserted through the opening 128 in the end member 14 directly over the aligned openings 44, 49 and 43, as shown in Fig. 5. In this position it is only necessary to raise the character from the printing drum through the transfer mechanism into this resilient tube, which will hold it and may then be removed with it. Thereafter, after the proper characters have been set by the transfer mechanism, the tube is returned with so much of the type in it as is utilisable and this type is shoved out of the tube and into the channel 87 by any suitable push rod inserted from the upper end. To shove the type from the printing drum into this emergency channel, I provide a suitable shoving implement, such as that shown at 35 127, Fig. 11, which has a tine 129 slightly longer than the distance between the drums, that is, from the outside of one slide to the outside of the other. If this tine is caused to engage the under side of the type in the printing drum which is to be replaced and is shoved upward to the limit of its movement, this type will come into the lower end of the resilient spring tube in the clip 125 and will be there retained.
- 45 It will be noticed from Fig. 7 that when the supply drum is lowermost an open channel is provided through the openings 43, 48 and 44 directly from outside the machine into the supply drum. This allows the type 50 to be initially assembled on the supply drum very easily, and also allows the distribution of type from the emergency tube, which may be held by hand over the opening 43.
- In place of making one drum larger than the other, it is possible to obtain the offset desired by mounting the drums eccentrically, in which case they may be of the same size. Such arrangement may bring the tails of the two drums into alignment at a certain point, which facilitates the making of corrections, it being only necessary to unlock a suitable opening through the frame member 16 to allow type to be shoved from a channel of one drum to a channel of the other.
- To provide a convenient table for the paper being fed to and from the machine when in printing position, as well as to allow sufficient room for the machine to swing into its transfer position, I provide a pair of slides 110 and 111 at the front and rear of the stand 10. When the multigraph is in position for printing, as shown in Figs. 2 and 4, these slides align with the top surface of the frame plate 113 through which the plate projects, each slide having an overhanging edge adapted to engage a rabbet at the corresponding edge of the frame plate 113. The bolts 34 and 35 pass loosely through the down-turned flanges 115 of the stand top 116 and are secured to the down-turned flanges of the plates 110 and 111. Thus as these plates are drawn outwardly to release the multigraph, the slides 110 and 111 are also drawn outwardly, as shown in Fig. 1, allowing sufficient room for the machine to turn. Suitable collars 118 on the bolts form stops limiting this movement. When the multigraph is in its vertical or transferring position as shown in Fig. 1, it is there locked by a suitable pin 119 carried by the stand and adapted to engage either of two openings 120 and 121 in the base of the multigraph.
- It will be seen from the above description that my machine is simple in construction and has few parts to get out of order. It saves a large amount of mechanism over machines wherein the transfer is made from one drum to the other while horizontal. Inasmuch as the purpose of this machine is to produce many copies of matter, the machine when constantly in use will not have to be turned up into transferring position many times a day. When it is to be so turned, the simple withdrawal of the bolts allows the machine to be easily swung. When in position the stand forms an excellent support for the machine for printing, the multigraph closing the opening in the upper face thereof and the slides forming an excellent paper table.
- I claim:
1. The combination of a printing member, a storage member, and means for holding them with either member elevated with reference to the other whereby the type may be moved by the assistance of gravity from either member to the other.
  2. The combination of a printing member, a storage member, and means for holding them with either member elevated with reference to the other, and means for laterally transferring the type.
  3. The combination of a printing member, a storage member, means for holding either member elevated with reference to the other, and finger keys for laterally moving the type allowing gravity to move them to the lower member.

4. The combination of a printing member and a storage member, means for supporting them so that either may be higher than the other, and means for releasing type from either member.
5. The combination of a storage member, a printing member, type adapted to be transferred from either to the other by assistance of gravity, and means enabling either member to be positioned above the other.
- 10 6. The combination of a storage member, a printing member, type adapted to be transferred from either to the other by lateral transference and assistance of gravity.
- 15 15 means for producing such lateral transference, and means enabling either member to be positioned above the other.
- 20 7. The combination of a storage member, a printing member, keys adapted to control the transfer of type from either to the other, and means enabling either member to be positioned above the other to avail of the factor of gravity for the transference of the type.
- 25 8. The combination of a storage member and a printing member mounted end to end, type adapted to be transferred from either to the other by assistance of gravity, and means enabling either member to be positioned above the other.
- 30 9. The combination with a platen of a printing member, means for releasing type to pass into it by gravity and means for receiving type passing from it by gravity.
- 35 10. The combination with a platen of a printing member, means for laterally transferring type and allowing them to pass into the printing member by gravity, and means for receiving type passing out of the printing member by gravity and laterally transferring them.
- 40 11. The combination of a printing member arranged for receiving and discharging type at the same end, means for holding that end elevated or depressed, means for feeding type thereto and therefrom, and finger keys for controlling the action.
- 45 12. The combination of a printing member movable to bring either end uppermost and means for feeding type thereto and therefrom by the assistance of gravity.
- 50 13. The combination of a rotary printing drum supported to have either end uppermost and means for feeding type thereto or therefrom by the assistance of gravity in each case.
- 55 14. The combination of a pivotally mounted frame and a supply member and a printing member mounted therein, and type transfer mechanism varied in its operation by swinging the frame on its pivot.
- 60 15. The combination of a pivotally mounted frame, a supply member and a printing member mounted therein and having type holders out of alignment, and means for lat- erally moving type from a position alining with one holder to a position alining with the other.
- 65 16. The combination of a pivotally mounted frame, a supply member and a printing member mounted therein, the swinging of the frame on its pivot bringing either member higher than the other, and finger mechanism for controlling the release of the type from the uppermost member.
- 70 17. The combination of a pivotally mounted frame, a supply drum and a printing drum mounted therein, and a pair of finger keys for controlling the release of type from the two drums, respectively, according to which stands relatively higher.
- 75 18. The combination of a pivotally mounted frame, a storage member and a printing member mounted therein, type formed to constitute a part of the machine, and means for transferring them by the assistance of gravity from either member to the other.
- 80 19. The combination of a pivotally mounted frame, a storage member and a printing member mounted therein and both having type holders out of alignment, and slides for transferring type by the assistance of gravity from either member to the other.
- 85 20. The combination of a pivotally mounted frame, a storage member and a printing member mounted therein, and finger controlled means for transferring type by the assistance of gravity from either member to the other.
- 90 21. The combination of a pivotally mounted frame, a storage drum and a printing drum, a pair of finger operated slides for transferring type by the assistance of gravity from either drum to the other.
- 95 22. The combination of a printing drum and a storage drum mounted end to end, said drums having type holders adapted to be out of alignment and a transfer slide having type holding means adapted to align with either drum.
- 100 23. The combination of a printing drum, a storage drum mounted end to end, one of said drums being of larger diameter than the other, and a transfer slide having type holding means adapted to align with either drum.
- 105 24. The combination of a printing drum, a storage drum mounted end to end, one of said drums being of larger diameter than the other, and a pair of transfer slides having type holding means adapted to align with either drum and with each other.
- 110 25. The combination of a channeled drum and a channeled storage drum mounted end to end, and a finger operated transfer slide having a type holding opening adapted to align with channels of either drum.
- 115 26. The combination of a pivoted frame, a pair of drums mounted therein end to end, said drums having type holders out of alignment.

- ment, and a transfer slide having an opening adapted to aline with a holder of either drum.
27. The combination of a pivoted frame, 5 a pair of channeled drums mounted therein end to end, one of said drums being of larger diameter than the other, a frame member between them, and a transfer slide mounted in such intermediate frame member and having an opening adapted to aline with a channel of either drum.
28. The combination of a pivoted frame, 10 a pair of type holding drums mounted therein end to end, a frame member between them, a transfer slide mounted in such intermediate frame member and having an opening adapted to aline with a holder of either drum, and finger mechanism for operating said slide.
29. The combination of a pivoted frame, 15 a pair of type holding drums mounted therein end to end, a frame member between them, a pair of transfer slides mounted in such intermediate frame member and having openings adapted to aline with a type holder of either drum.
30. The combination of two cylindrical drums mounted end to end with typeholders out of circumferential alinement, and 20 a transfer slide between them.
31. The combination of two drums mounted end to end, a frame member between them, and two transfer slides mounted in said frame member, one for assembling and 25 one for distributing.
32. The combination of two drums mounted end to end, a frame member between them, transfer slides mounted in said frame member, and finger keys for operating said 30 slides.
33. The combination of two drums mounted end to end, transfer slides between them, and a controlled opening between the transfer slides.
34. The combination of two drums mounted end to end, a frame member between them, transfer slides mounted in said frame member, and a movable block between the transfer slides.
35. The combination of two drums mounted end to end, a member between them, transfer slides mounted in said member, a 40 movable block between the transfer slides, means for positioning the block, and finger keys for moving the slides.
36. The combination of a movable frame, two drums mounted end to end in such movable frame, transfer slides between said ends, and means whereby the position of 45 the frame determines the activity of the slides.
37. The combination of two type holding members, either adapted to stand above the other, an intermediate member and a pair 50 of slides mounted in said intermediate mem- ber adjacent to the ends of the respective type holding members, each slide having a type receiving opening adapted to aline with either of said members.
38. The combination of two type holding 70 members, either adapted to stand above the other, an intermediate frame member, a pair of slides mounted in said frame member adjacent to the ends of the respective type holding members, each slide having a type 75 receiving opening adapted to aline with either of said members, and a pair of finger keys for said slides.
39. The combination of a frame, two type- 80 holding members mounted in such frame and adapted to stand either above the other but out of alinement, and an intermediate slide having a type receiving opening adapted to aline with either of said mem- bers.
40. The combination of two type holding 85 members, an intermediate member, and a pair of slides mounted in said intermediate member adjacent to the ends of the respective type holding members, each slide having a type 90 receiving opening adapted to aline with either of said members, there being an opening in the intermediate frame member between the slides.
41. The combination of two type holding 95 members, an intermediate member, a pair of slides mounted in said intermediate member adjacent to the ends of the respective type holding members, each slide having a type receiving opening adapted to aline 100 with either of said members, and a movable block occupying an intermediate opening in the intermediate member.
42. The combination of two type holding members out of alinement, an intermediate 105 member, a pair of slides mounted in said intermediate member adjacent to the ends of the respective type holding members, each slide having a type receiving opening adapted to aline with either of said members, there being two type receiving openings in the member, alining with the two type hold- 110 ers respectively.
43. The combination of two type holding 115 members, either adapted to stand above the other, an intermediate frame member, a pair of slides mounted in said frame member adjacent to the ends of the respective type holding members, each slide having a type receiving opening adapted to aline with 120 either of said members, a pair of type open- 125 ings through the frame member, and a block occupying an intermediate opening in the frame member and controlling the type openings therein.
44. The combination of a frame, a storage member and a printing member mounted therein, said frame being adapted to be turned to bring either member above the other, and a finger key for controlling the 130

- transference of type from the member which is above to the lower member.
45. The combination of a frame, a storage member and a printing member mounted therein, said frame being adapted to be turned to bring either member above the other, and a pair of finger keys for controlling the transference of type from the upper member to the lower member.
- 10 46. The combination of a frame, a storage member, a printing member, a co-operating platen all mounted in said frame which is adapted to be turned to bring either member above the other, and means for controlling the transference of type from the upper member to the lower member.
- 20 47. The combination of a frame, a storage member and a printing member mounted in said frame which is adapted to be turned to bring either member above the other, a pair of finger keys for controlling the transference of type from the upper member to the lower member, and means for rendering one of said keys ineffective.
- 30 48. The combination of a storage member and printing member mounted in a frame adapted to be turned to bring either member above the other, a pair of finger keys for controlling the transference of type from the upper member to the lower member, and means for automatically rendering ineffective one key or the other when one member or the other is moved into uppermost position.
- 35 49. The combination of a storage drum, a printing drum mounted end to end in a frame adapted to be turned to bring either drum above the other, a pair of finger keys mounted between the drums for controlling the transference of type from the upper drum to the lower, and means for automatically rendering ineffective one key or the other when one drum or the other is swung into uppermost position.
- 45 50. The combination of a storage member, a printing member, a platen, a pivoted frame, in which all of said members are mounted, said frame being adapted to be turned to bring either member above the other, a pair of finger keys mounted between the members for controlling the transference of type from the upper member to the lower member, and means for automatically rendering ineffective one key or the other when one drum or the other is swung into uppermost position.
- 50 51. The combination of a storage member and printing member, a frame in which said members are mounted, a pair of standards to which said frame is pivoted to allow either member to be uppermost, and finger mechanism for controlling the transference of type from the upper member to the lower member.
- 60 52. The combination of two type-holding drums one larger than the other and mounted end to end, and a type channel adapted to be held on the inside of the larger drum in substantial alignment with the outside of the smaller drum.
- 70 53. The combination of two multichanneled drums, one of larger diameter than the other, a tubular type-holder, and means on the interior of the larger drum for holding such type-holder.
- 75 54. The combination of a stand and a device comprising a storage drum, a printing drum, a platen and an inking ribbon, said device being pivotally mounted on the stand.
- 80 55. The combination of a stand having an open top, a device pivotally carried by the stand and including a printing member, said device being adapted to stand horizontally over the top or to be turned to bring either end of the printing member uppermost.
- 85 56. The combination of a stand having an open top, a device pivotally carried by the stand and comprising a storage member and a printing member, said device being adapted to stand horizontally over the top or to be turned to bring either member into the open space in the top.
- 90 57. The combination of a stand having an open top with an adjacent portion adapted to constitute a table and a printing member and a platen pivotally carried by the stand and adapted to swing down into the opening and to be positioned so that the surface of the table is adjacent to the line of contact of the printing member and platen.
- 95 58. The combination of a stand having an open top, a printing member and platen, which, as a whole, are pivotally carried by the stand and adapted to be positioned so that the top of the stand makes a feed table approximately aligning with the line of contact of the printing member and platen.
- 100 59. The combination of a stand having an open top, a printing member pivotally carried by the stand and adapted to be positioned substantially horizontally so that the top of the stand makes a feed table said printing member being adapted to swing down into the opening, and bolts for locking said member in either position.
- 105 60. The combination of a stand having an open top, a printing couple pivotally carried by the stand and adapted to be positioned horizontally or to swing down into the stand, and means for locking said couple in either position.
- 110 61. A device comprising a printing member, platen, and transfer fabric and a stand on which said device is pivotally mounted.
- 115 62. A device comprising a storage member, a printing member and transfer mechanism and a stand on which said device is pivotally mounted.
- 120 63. A device comprising a printing member and assemblage and distribution mech-
- 125 130

anism, and a stand on which said device is pivotally mounted, whereby the device may stand horizontally or with either end uppermost, the position of the device controlling said mechanism.

6. A device comprising a storage member, a printing member and transfer mechanism, and a stand on which said device is pivotally mounted, whereby the device may stand horizontally or with either end uppermost, the position of the device controlling the transfer mechanism.

10. 64. The combination of a printing device comprising a type carrying member and platen, and a stand on which said device is pivotally mounted, whereby the device may be turned to allow type to be fed by gravity.

15. 65. The combination of a printing device comprising a type carrying drum and rotary platen, and a stand on which said device is pivotally mounted, whereby the device may be turned to allow type to be fed by gravity.

20. 66. The combination of a printing device comprising a type carrying drum and rotary platen, and a stand on which said device is pivotally mounted, whereby the device may be turned to allow type to be fed by gravity, the top of the stand when the device is horizontal approximately alining with the space between the printing member and platen to form a feed table.

25. 67. The combination of a printing device comprising a type carrying member and platen, and a stand on which said device is pivotally mounted, whereby the device may be turned to allow type to be fed by gravity, the top of the stand when the device is horizontal approximately alining with the space between the printing member and platen to form a feed table.

30. 68. The combination of a device comprising a type carrying printing member, a platen and a storage member, and a stand on which said device is pivotally mounted between said members, whereby the device may be turned to allow type to be fed by gravity from either member to the other, the top of the table when the device is horizontal approximately alining with the space between the printing member and platen to form a feed table.

35. 69. The combination of a type carrying member and means for holding it horizontal or turning it either end uppermost to allow type to be fed into it or out of it by gravity.

40. 70. The combination of a rotary channeled drum, and a pivoting support for holding it horizontal or allowing it to be turned either end uppermost to allow type to be fed in or out of it by gravity.

45. 71. The combination of a printing couple, and means for pivotally supporting it, whereby it may be swung into position to have type fed by gravity.

50. 72. The combination of a printing couple, and means for pivotally supporting it, whereby it may be swung in either direction to have type fed by gravity into or out of it.

55. 73. The combination of a rotary printing drum, a coöperating platen, and means for pivotally supporting the drum transversely

of its axis of rotation, whereby it may be swung into position to enable type to be fed to or from it by gravity.

60. 74. The combination of a rotary printing drum, a coöperating rotary platen, and means for pivotally supporting both the drum and platen transversely of their axes of rotation, whereby they may be swung into position to enable type to be fed to or from said drum by the assistance of gravity.

70. 75. The combination of a unitary structure having two multi-channeled members, means for pivotally mounting such structure, means for transferring type from either member to the other, and mechanism whereby the swinging of said structure on its pivot controls the last-mentioned means.

75. 76. The combination of a storage member, a printing member, and transfer mechanism, a frame in which such parts are mounted to constitute a unitary structure, said structure being pivotally mounted so that it may stand either end up, and means whereby such interchange of position varies the control of the transfer mechanism.

80. 77. The combination of a printing member, a storage member, transfer mechanism, a pair of finger keys for controlling the same, and means for pivotally supporting such structure as a whole, whereby the printing member and the storage member may be interchanged as to their relative altitude, and means whereby such interchange varies the effect of the transfer mechanism.

85. 78. The combination of a printing member, a storage member, transfer mechanism, a pair of finger keys for controlling the same, means for tipping the printing member and storage member relatively to each other, and means whereby such interchange render ineffective one of said keys and releases the other respectively.

90. 79. The combination of two type holding members, and two intermediate transfer slides, one for assembling and one for distributing.

95. 80. The combination of two type holding members, end to end, two transfer slides adjacent to the proximate ends of said members respectively, and a guiding member intermediate of said slides.

100. 81. The combination of a printing drum, a storage drum, a frame member between them, a transfer opening through said frame member, and a transfer slide having an opening adapted to aline with the opening mentioned.

105. 82. The combination of a printing drum, a storage drum, a frame member between them, a transfer opening through said frame member, and transfer slides between the respective drums and the frame member, each having an opening adapted to aline with the opening mentioned.

110. 83. The combination of a storage member,

1. A printing member, each having in its surface longitudinal type-holders, the holders of the two members being adapted to be out of alignment, and a member intermediate of the members mentioned, having two transfer openings adapted to aline with type-holders of those two members respectively. 5
2. The combination of a storage drum, a printing drum, each having in its surface longitudinal type-holders, the holders of the two drums being adapted to be out of alignment, a member intermediate of the drums having two transfer openings adapted to aline with type-holders of the two drums respectively, and means for controlling admission to said openings. 10
3. The combination of a storage drum, a printing drum, each having in its surface longitudinal type-holders, the holders of the two drums being adapted to be out of alignment, a member intermediate of the drums having two transfer openings adapted to aline with type-holders of the two drums respectively, and a block for obstructing one opening or the other. 15
4. The combination of a storage member, a printing member, each having in its surface longitudinal type-holders, the holders of the two members being adapted to be out of alignment, a member intermediate of the drums having two transfer openings adapted to aline with type-holders of the two members respectively, and a pair of slides for controlling admission to said openings respectively. 20
5. The combination of a storage drum, a printing drum, each having in its surface longitudinal type-holders, the holders of the two drums being adapted to be out of alignment, a member intermediate of the drums having two transfer openings adapted to aline with type-holders of the two members respectively, and a block occupying such communication, and means for causing said block to occupy either of two extreme positions to open either opening and close the other. 25
6. The combination of a storage drum, a printing drum, each having in its surface longitudinal type-holders, the holders of the two drums being adapted to be out of alignment, a member intermediate of the drums having two transfer openings adapted to aline with type-holders of the two members respectively, and openings communicating, a block occupying such communication, and means for causing said block to occupy either of two extreme positions to open either opening and close the other. 30
7. The combination of a storage drum, a printing drum, each having in its surface longitudinal type-holders, the holders of the two drums being adapted to be out of alignment, a member intermediate of the drums having two transfer openings adapted to aline with type-holders of the two members respectively, means adapted to open either opening and close the other, and a pair of transfer slides, cooperating with the two members respectively. 35
8. The combination of a storage drum, a printing drum, each having in its surface longitudinal type-holders, the holders of the two drums being adapted to be out of alignment, a member intermediate of the drums having two transfer openings adapted to aline with type-holders of the two members respectively, means adapted to open either opening and close the other, and means whereby the movement into such position controls assemblage and distribution of type. 40
9. The combination of a storage drum, a printing drum, each having in its surface longitudinal type-holders, the holders of the two drums being adapted to be out of alignment, a member intermediate of the drums having two transfer openings adapted to aline with type-holders of the two members respectively, a block adapted to close either opening and thereby open the other, said drums being mounted so that either may stand above the other, and means whereby the movement into such position correspondingly shifts the block. 45
10. The combination of a storage member, a printing member, and a transfer mechanism, a pivoted structure carrying all of such parts, and gearing operated by movement about such pivot to vary the transfer mechanism. 50
11. The combination of a storage drum, a printing drum, each having in its surface longitudinal type-holders, slides intermediate of the drums having transfer openings adapted to aline with type-holders of the two drums respectively, a pivotal support for the whole structure described, a stationary rack, and gearing carried by such pivoted structure and adapted to engage said stationary rack to shift said slides. 55
12. The combination of a storage drum, a printing drum, each having in its surface longitudinal type-holders, a member intermediate of the drums having two transfer openings adapted to aline with type-holders of the two members respectively, a block for controlling said openings, a pivotal support for the whole structure described, a stationary rack, and gearing carried by such pivoted structure and adapted to engage said stationary rack to shift said block. 60
13. The combination of a storage drum, a printing drum, each having in its surface longitudinal type-holders, a member intermediate of the drums having two transfer openings adapted to aline with type-holders of the two members respectively, a block occupying such communication, and means for causing said block to occupy either of two extreme positions to open either opening and close the other. 65
14. The combination of a storage member, a printing member, each having type-holders, an intermediate member having two transfer openings adapted to aline with type-holders of the two members respectively, and a pair of slides on opposite sides respectively of said intermediate member and having openings adapted to aline with respective type-holders and the corresponding openings through said member. 70
15. The combination of a storage drum and a printing drum mounted end to end and each having in its surface longitudinal type-holders, the holders of the two drums being adapted to be out of alignment, a member intermediate of the drums having two transfer openings adapted to aline with type-holders of the two members respectively, and a pair of slides on opposite sides respectively of said member and having openings adapted to aline with respective type-holders and the corresponding openings through said member. 75
16. The combination of two type-holders, a member intermediate thereof having two 80
17. The combination of a storage drum, a printing drum, each having in its surface longitudinal type-holders, the holders of the two drums being adapted to be out of alignment, a member intermediate of the drums having two transfer openings adapted to aline with type-holders of the two members respectively, a block occupying such communication, and means for causing said block to occupy either of two extreme positions to open either opening and close the other. 85
18. The combination of a storage member, a printing member, each having type-holders, an intermediate member having two transfer openings adapted to aline with type-holders of the two members respectively, and a pair of slides on opposite sides respectively of said intermediate member and having openings adapted to aline with respective type-holders and the corresponding openings through said member. 90
19. The combination of a storage drum, a printing drum, each having in its surface longitudinal type-holders, a member intermediate of the drums having two transfer openings adapted to aline with type-holders of the two members respectively, a block occupying such communication, and means for causing said block to occupy either of two extreme positions to open either opening and close the other. 95
20. The combination of a storage drum, a printing drum, each having in its surface longitudinal type-holders, the holders of the two drums being adapted to be out of alignment, a member intermediate of the drums having two transfer openings adapted to aline with type-holders of the two members respectively, a block occupying such communication, and means for causing said block to occupy either of two extreme positions to open either opening and close the other. 100
21. The combination of a storage member, a printing member, each having type-holders, an intermediate member having two transfer openings adapted to aline with type-holders of the two members respectively, and a pair of slides on opposite sides respectively of said intermediate member and having openings adapted to aline with respective type-holders and the corresponding openings through said member. 105
22. The combination of a storage drum and a printing drum mounted end to end and each having in its surface longitudinal type-holders, the holders of the two drums being adapted to be out of alignment, a member intermediate of the drums having two transfer openings adapted to aline with type-holders of the two members respectively, and a pair of slides on opposite sides respectively of said member and having openings adapted to aline with respective type-holders and the corresponding openings through said member. 110
23. The combination of two type-holders, a member intermediate thereof having two 115
24. The combination of a storage drum, a printing drum, each having in its surface longitudinal type-holders, the holders of the two drums being adapted to be out of alignment, a member intermediate of the drums having two transfer openings adapted to aline with type-holders of the two members respectively, a block occupying such communication, and means for causing said block to occupy either of two extreme positions to open either opening and close the other. 120
25. The combination of a storage drum and a printing drum mounted end to end and each having in its surface longitudinal type-holders, the holders of the two drums being adapted to be out of alignment, a member intermediate of the drums having two transfer openings adapted to aline with type-holders of the two members respectively, and a pair of slides on opposite sides respectively of said member and having openings adapted to aline with respective type-holders and the corresponding openings through said member. 125
26. The combination of two type-holders, a member intermediate thereof having two 130

- transfer openings adapted to aline with such type holders respectively, and a pair of slides on opposite sides respectively of said member and having openings adapted to aline with respective type holders and the corresponding openings through said member, and means for automatically moving said slides to bring them normally in registration with one opening or the other.
97. The combination of a rotary storage drum, a rotary printing drum, each having in its surface longitudinal type holders, the holders of the two drums being adapted to be out of alinement, a member intermediate of the drums having two transfer openings adapted to aline with type holders of the two drums respectively, and a pair of slides on opposite sides respectively of said member and having openings adapted to aline with respective type holders and the corresponding openings through said member, and means for automatically moving said slides to bring them normally in registration with one opening or the other.
98. The combination of a pair of type holding members, a pair of transfer slides between them, each having a transfer opening, and means for holding both of said slides with their openings in alinement with one of said type holders.
99. The combination of a pair of type holding members out of alinement, a pair of transfer slides between them, each having a transfer opening, and means for holding both of said slides with their openings out of alinement with either type holder.
100. The combination of a pair of type holding members out of alinement, a pair of transfer slides between them, each having a transfer opening, and means for holding said slides with both of their openings concurrently in alinement with either type holder.
101. The combination of a pair of type holding members, a pair of transfer slides between them, each having a transfer opening, means for holding said slides with their openings in alinement with either type holder, and means for automatically positioning said slides according to which type holder is lowermost.
102. The combination of a pair of type holding members out of alinement, a pair of slides adjacent to the ends of said members, another member between said slides, said last mentioned member having a pair of openings through it alining with the two type holders respectively, and said slides having each an opening adapted to aline with either of the type holders.
103. The combination of a pair of type holding drums, a pair of slides adjacent to the ends of said drums, another member between said slides, said last mentioned member having a pair of openings through it alining with the type holders of the two drums respectively, and said slides having each an opening adapted to aline with either of the type holders.
104. The combination of a pair of type holding members, a pair of slides adjacent to the ends of said members, another member between said slides, said last mentioned member having a pair of openings through it alining with the two type holders of the type holding members respectively, said slides having each an opening adapted to aline with either of the type holders, and means for blocking either opening through said intermediate member.
105. The combination of a pair of type holding drums end to end, a pair of slides adjacent to the proximate ends of said drums, a member between said slides, said member having a pair of openings through it alining with two type holders of the two drums respectively, said slides having each an opening adapted to aline with either of the type holders, and a shiftable block for blocking either opening through said intermediate member.
106. The combination of a pair of type holding members, a pair of slides adjacent to the ends thereof, said slides having each an opening adapted to aline with either of the type holders, and means for controlling the passageway between said slides.
107. The combination of a pair of type holding members, a pair of slides adjacent to the ends of said members, said slides having each an opening adapted to aline with either of the type holders, two passageways between said slides, mechanism for blocking either passageway, and mechanism for varying the position of said slides controlled by such blocking mechanism.
108. The combination of a pair of type holding members, a pair of slides adjacent to the ends of said members, said slides having each an opening adapted to aline with either of the type holders, a plurality of passageways between said slides, a block for controlling such passageways, two levers for controlling the initial position of said slides respectively, and links connecting said levers respectively with said block.
109. The combination of a pair of type holding members, a pair of slides adjacent to the ends of said members, said slides having each an opening adapted to aline with either of the typeholders, there being two openings between the slides, a block for blocking either of the two openings last mentioned, and an eccentric for shifting said block.
110. The combination of a pair of type holding members, a pair of slides adjacent to the ends of said members, said slides having each an opening adapted to aline with either of the type holders, a passage-

- way between said slides, an eccentric for controlling it, gearing for operating said eccentric, and a stationary rack for driving said gearing when said type holders are 5 swung into different relative altitude.
111. The combination of a pair of type holders, a pair of transfer slides, and springs tending to hold one of said slides in its foremost position and the other in its rear-most position.
112. The combination of a pair of type holders, a pair of transfer slides, springs tending to hold one of said slides in its foremost position and the other in its rear-most position, and finger mechanism enabling one slide to be pushed and the other to be pulled.
113. The combination of a pair of type holders out of alinement, a pair of transfer slides between them, and springs tending to move said slides in opposite directions into registration with either type holding member, and means for rendering either slide ineffective.
114. The combination of a pair of type holders out of alinement, a pair of transfer slides between them, means for holding said slides in registration with either type holding member, one of the slides being held 25 positively and the other by a spring, whereby said last mentioned slide may be moved.
115. The combination of two type holders, two transfer slides between their ends, means for positioning either type holder 30 above the other, and automatic means for holding the slide adjacent to the undermost type holder, and freeing the other slide.
116. The combination of two type holders out of alinement, two transfer slides between their ends, springs constraining one 35 slide forward and the other rearward, means for positioning either type holder above the other, and automatic means for holding the slide adjacent to the undermost type holder, and freeing the other slide.
117. The combination of a pair of type holders out of alinement and a pair of transfer slides between them adapted to transfer type from either to the other.
118. The combination of a pair of rotatable drums having type holders out of circumferential alinement and a pair of transfer slides between said drums adapted to transfer type from either drum to the other.
119. The combination of a pair of type holders out of alinement and a pair of transfer slides between them, each transfer slide having a type receiving opening, which two openings are adapted to aline with either 55 holder.
120. The combination of a pair of rotatable drums having type holders out of alinement and a pair of transfer slides between said drums, each transfer slide having 60 a type receiving opening, which two open- ings are adapted to aline with holders of either drum.
121. The combination of a pair of type holders out of alinement and a pair of transfer slides between them, each transfer slide 70 having a type receiving opening, which two openings are adapted to aline with either holder, and means whereby either holder may be positioned above the other.
122. The combination of a pair of type 75 holders out of alinement and a pair of transfer slides between them, each transfer slide having a type receiving opening, which two openings are adapted to aline with either holder, means whereby either holder may be 80 positioned above the other, and means whereby the two openings in the two slides are caused to automatically assume a position in registration with the lowermost type holder.
123. The combination of a pair of type 85 holders out of alinement and a pair of transfer slides between them, each transfer slide having a type receiving opening, which two openings are adapted to aline with either 90 holder, means whereby either holder may be positioned above the other, means for holding the lowermost slide with its opening in alinement with the lowermost type holder, and a spring for normally holding the uppermost slide in this position but allowing it to be moved against the action of the 95 spring to cause its opening to aline with the other type holder.
124. The combination of a pair of type 100 holders out of alinement and a pair of transfer slides between them, each transfer slide having a type receiving opening, which two openings are adapted to aline with either 105 holder, means whereby either holder may be positioned above the other, and means whereby the two openings in the two slides are caused to automatically assume a position in registration with the lowermost type 110 holder, means for positively holding the lowermost slide in this position, and a spring for normally holding the uppermost slide in this position but allowing it to be moved against the action of the spring to cause its opening to aline with the other type 115 holder.
125. The combination of a printing member, a storage member, and means on opposite ends of said members for moving the storage member.
126. The combination of a printing member, a storage drum, a pair of hand wheels on opposite ends, one on one end of said drum and the other beyond the other end of the printing member and both adapted to turn said drum on its axis.
127. The combination of a storage member and a printing member mounted end to end, a pair of mechanisms at the distant ends of the two members, and means whereby either 125 130

of said mechanisms may move the storage member.

128. The combination of a storage drum and a printing drum mounted end to end, a 5 pair of hand wheels at the distant ends of the two drums, and means whereby either hand wheel may rotate the storage drum.

129. The combination of a storage drum and a printing drum, mounted end to end, 10 and means at the end of the printing drum which is farthest from the storage drum for turning said storage drum.

130. The combination of a storage drum and a printing drum, mounted end to end, 15 means at the end of the printing drum which is farthest from the storage drum for turning said storage drum, and means at the free end of the storage drum for turning it.

131. The combination of a printing drum, a storage drum, a shaft for said storage drum extending through the printing drum, and means on said shaft beyond the far end of the printing drum for turning the storage 25 member.

132. The combination of a storage drum, a shaft on which the same is mounted extending beyond each end of the storage drum, a printing drum mounted around 30 said shaft, and a hand wheel on each end of said shaft for rotating the storage drum.

133. The combination of a storage drum, a projecting shaft therefor, a printing drum mounted around said shaft, a crank for rotating said printing drum, and a hand wheel on said shaft beyond the shank of the crank for rotating the storage drum, the crank projecting beyond the hand wheel whereby it may be driven.

134. The combination of a printing drum, a sleeve on which the same is mounted, means engaging the projecting end of the sleeve for driving the printing drum, a shaft projecting through said sleeve, a storage drum on said shaft, and means beyond 45 the printing drum for rotating said shaft and thereby turning the storage drum.

135. The combination of a printing drum, a sleeve on which the same is mounted, a 50 crank on the projecting end of the sleeve for driving the printing drum, a shaft projecting through said sleeve, a storage drum on said shaft, and means beyond the printing drum for rotating said shaft and thereby turning the storage drum, said shaft extending beyond the storage drum in the opposite direction and means on this end of the shaft for rotating it.

136. The combination of a type storage 60 member, a hand wheel for turning it, an indicating chart on the hand wheel, and a telescoping pointer adapted to cooperate with the chart.

137. The combination of a type storage

drum having a shaft, a coaxial printing 65 drum loose on such shaft, a crank for rotating the printing drum, and a hand wheel on said shaft on the outer side of the radial portion of the crank, the handle of the crank extending beyond the outer side of the hand 70 wheel.

138. The combination of a rotary storage drum, hand wheels at each end thereof for rotating it and a pivotal support for the drum transverse to the axis of rotation. 75

139. The combination of a channeled storage drum adapted to stand with its channels vertical hand wheels above and below said drum for turning it about an axis and a pivotal support for the drum transverse to 80 its axis of rotation.

140. The combination of a storage drum, means at each end thereof for turning it, a pivotal support for the drum whereby it may be inverted, and means for distributing 85 type into the drum and assembling type from it according to which end is uppermost.

141. The combination of a printing couple, a storage drum at one end of the couple, a pivoted frame for carrying all of such parts, and means at both ends of the frame for turning the storage drum.

142. The combination, with a pivotally mounted frame, of a storage drum, a printing drum, said two drums being mounted end to end in such pivotally mounted frame, whereby either drum may be turned uppermost, and means at each end of the frame for turning the storage drum. 90

143. The combination, with a pivotally mounted frame, of a storage drum, a printing drum, said two drums being mounted end to end in such pivotally mounted frame, whereby either drum may be turned uppermost, a hand wheel at each end of the frame for turning the storage drum, a chart in the periphery of said hand wheels, and pointers coöperating with said charts. 100

144. The combination, with a pivotally mounted frame, of a storage drum, a printing drum, said two drums being mounted end to end in such pivotally mounted frame, whereby either drum may be turned uppermost, means for turning the storage drum, 110 and means for controlling the transfer between the drums. 115

145. The combination, with a pivotally mounted frame, of a storage drum, a printing drum, said two drums being mounted end to end in such pivotally mounted frame, whereby either drum may be turned uppermost and a hand wheel at each end of the frame for turning the storage drum, and means for controlling the transfer from 120 either drum to the other. 125

146. The combination of a storage member, a printing member and a coöperating

platen, and a frame carrying all of said parts and pivotally mounted.

147. The combination of a storage member, a printing member, a coöperating platen, an intermediate inking ribbon, and a frame carrying all of said parts and pivotally mounted.

148. The combination, with a frame, of a storage member, a printing member, a co-
10 operating platen, said printing member being adapted to carry individual type on its periphery, means for removably holding a printing ribbon adjacent to such type, all of said parts being carried by said frame, said 15 frame being pivotally mounted whereby either the storage member or the printing member may be turned uppermost to feed type by gravity.

149. The combination, with a frame, of a storage member, a printing member, a finger operated transfer mechanism between them, a platen, said printing member being adapted to carry individual type on its periphery, all of said parts being carried by 25 said frame, said frame being pivotally mounted whereby either the storage member or the printing member may be turned uppermost to feed type by assistance of gravity and said transfer mechanism.

150. The combination of a storage drum, a printing drum mounted end to end therewith, ribbon spools carried by the printing drum, individual type adapted to be carried by either drum and transferable from one 35 to the other, a rotary platen coöperating with the printing drum, a paper feeding roller for the platen, a frame on which all of said parts are mounted, and a pivotal support for said frame, whereby either drum 40 may be turned uppermost.

151. The combination of a storage drum, a printing drum mounted end to end therewith, ribbon spools carried by the printing drum, individual type adapted to be carried 45 by either drum and transferable from one to the other, a rotary platen coöperating with the printing drum, a paper feeding roller for the platen, a frame on which all of said parts are mounted, a pivotal support 50 for said frame, whereby either drum may be turned uppermost, transfer mechanism for controlling the transfer from the uppermost drum to the lower, and mechanism for controlling the transfer mechanism according to the position of the drums.

152. The combination of a storage member, a printing member, an intermediate frame member and journal pins engaging said frame member.

153. The combination of a storage drum, a printing drum, transverse frame members, longitudinal brace bars, and means for pivoting such structure.

154. The combination with two type hold-

ing members out of alinement, laterally 65 moving transfer means between them, and a push key and a pull key for operating such transfer means.

155. The combination with two typeholding members of two intermediate transfer 70 slides one effective on the forward mover ent and one on the rearward, and means tet ing to move one forward and the other rearward.

156. The combination of two cylindrical 75 type-holding drums, one adapted to extend transversely beyond the other, and laterally acting transfer mechanism.

157. The combination of two cylindrical type-holding drums, one adapted to extend 80 transversely beyond the other, and means providing an open passageway from outside the machine to the extending drum.

158. The combination of two type-holding drums mounted end to end, one extending at 85 its adjacent end transversely beyond the adjacent end of the other, and a transfer slide between the drums.

159. The combination of two independently rotatable drums one extending radially 90 beyond the other, transfer mechanism, and finger keys therefor.

160. The combination of two type-holding drums, one extending radially beyond the other, and two laterally movable transfer 95 slides between them.

161. The combination of two type-holding drums, one extending radially beyond the other, a temporary type holder, and means for holding it in alinement with the 100 type-holding means of one of the drums.

162. The combination of a pivotally mounted frame, typeholding members mounted therein and having their typeholders out of alinement, and means for laterally moving type from a position alining with one holder to a position alining with the other.

163. The combination of a pivotally mounted frame, typeholding members 110 mounted therein, adapted to be one above the other and finger mechanism for controlling the release of the type from the uppermost member.

164. The combination of a pivotally mounted frame, typeholding members 115 mounted therein, type formed to constitute a part of the machine, and means for transferring the type by the assistance of gravity from either member to the other.

165. The combination of a pivotally mounted frame, typeholding members mounted therein and both having typeholders out of alinement, and slides for transferring type by the assistance of gravity 125 from either member to the other.

166. The combination of a pivotally mounted frame, typeholding members

mounted therein, and finger controlled means for transferring type by the assistance of gravity from either member to the other.

5. 167. The combination of a printing couple, type assemblage and distribution mechanism coöperating with one member of the couple, a frame carrying such parts, a pair of bearing members between which the frame is pivoted, and gearing carried partly by the frame and partly by one of said bearing members and adapted to vary the assemblage and distribution mechanism when the frame is turned on its pivot.
15. 168. The combination of a frame, a pair of type transfer slides mounted thereon, a pivotal bearing for the frame, gearing carried partly by the frame and partly by such bearing for rendering one or the other of 20 said slides effective and the other idle when the frame is turned on its pivot, and two type-holding members with which said slides coöperate.
25. 169. A printing couple, a pivotally mounted frame therefor, and assemblage and distribution mechanism coöperating with the typecarrying member of the couple, and operative to assemble or distribute according to the position of the frame.
30. 170. A rotary type carrying drum pivotally supported on an axis transverse to its axis of rotation, whereby it may be tipped either end uppermost, and mechanism coöperating with it to assemble when one end 35 is uppermost and to distribute when the other end is uppermost.
171. A rotary drum pivotally mounted transverse of its axis of rotation, and finger-operated means for feeding type thereto and 40 therefrom.
172. A type-holding member mounted to turn on an axis and movable also on another and different axis, and means for feeding

type into and out of the same end of said member.

45

173. The combination of a stand, a frame pivotally mounted thereon and a rotary drum and a rotary platen, both mounted on said frame, the pivotal mounting of the frame being transverse to the axis of rotation of the drum, and assemblage mechanism adjacent to the end of the drum.

50

174. The combination of two type-holding cylindrical drums, one of larger diameter than the other, and laterally acting transfer mechanism.

55

175. The combination of two type-holding cylindrical drums, one of larger diameter than the other, and means providing an open passageway from outside the machine 60 to the larger drum.

60

176. The combination of two type-holding cylindrical drums mounted end to end, one of larger diameter than the other, and a transfer slide between the drums.

65

177. The combination of two independently rotatable typeholding drums, one of larger diameter than the other, transfer mechanism, for the type and finger keys therefor.

70

178. The combination of two type-holding drums, one of larger diameter than the other, and two laterally movable transfer slides between them.

75

179. The combination of two type-holding drums, one of larger diameter than the other, a temporary type-holder, and means for holding it in alinement with the type-holding means of one of the drums.

In testimony whereof, I hereunto affix my 80
signature in the presence of two witnesses.

ALBERT H. BATES.

Witnesses:

G. A. MYERS,
BRENNEN B. WEST.
